(57) **CLAIM**

The ornamental design for a three-part clasp for pumping garment, as shown and described.

DESCRIPTION

FIG. 1 is a front perspective view of a three-part clasp for pumping garment of a first embodiment of the present invention in a doubly fastened configuration;

FIG. 2 is a back perspective view of the three-part clasp for pumping garment illustrated in FIG. 1;

FIG. 3 is a top view of the three-part clasp for pumping garment illustrated in FIGS. 1 and 2;

FIG. 4 is a front view of the three-part clasp for pumping garment illustrated in FIGS. 1-3;

FIG. 5 is a left side view of the three-part clasp for pumping garment illustrated in FIGS. 1-4;

FIG. 6 is a right side view of the three-part clasp for pumping garment illustrated in FIGS. 1-5;

FIG. 7 is a back view of the three-part clasp for pumping garment illustrated in FIGS. 1-6;

FIG. 8 is a bottom view of the three-part clasp for pumping garment illustrated in FIGS. 1-7;

FIG. 9 is a front perspective view of a three-part clasp for pumping garment of a second embodiment of the present invention in a doubly fastened configuration;

FIG. 10 is a back perspective view of the three-part clasp for pumping garment illustrated in FIG. 9;

FIG. 11 is a top view of the three-part clasp for pumping garment illustrated in FIGS. 9 and 10;

FIG. 12 is a front view of the three-part clasp for pumping garment illustrated in FIGS. 9-11;

FIG. 13 is a left side view of the three-part clasp for pumping garment illustrated in FIGS. 9-12;

FIG. 14 is a right side view of the three-part clasp for pumping garment illustrated in FIGS. 9-13;

FIG. 15 is a back view of the three-part clasp for pumping garment illustrated in FIGS. 9-14; and,

(Continued)

FIG. 16 is a bottom view of the three-part clasp for pumping garment illustrated in FIGS. 9-15. The broken lines in FIGS. 9-16 of the drawings depict portions of the three-part clasp for pumping garment that form no part of the claimed design.
